[57] CLAIM

The ornamental design for an electric food warming vessel for restaurants and cafeterias, as shown and described.

DESCRIPTION

FIG. 1 is a top, front and right side perspective view of a food warming vessel showing my new design; FIG. 2 is a left side elevational view thereof, the right side being a mirror image; FIG. 3 is a front elevational view thereof; FIG. 4 is a rear elevational view thereof; FIG. 5 is a top plan view thereof; FIG. 6 is a bottom plan view thereof; FIG. 7 is a top front-end perspective view of another embodiment of my new design having a different form of cover; FIG. 8 is a front and rear elevational view of the cover shown in FIG. 7 with the cover separate for clarity of illustration only; FIG. 9 is a left and right side elevational view of the cover of FIG. 7 with the cover shown separately for clarity of illustration only. The electric cord shown broken away is understood to represent indeterminate length.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 349,421
DATED : August 9, 1994
INVENTOR(S) : Eugine W. Goad

It is certified that error appears in the above-indentified patent and that said Letters Patent is hereby corrected as shown below:

Title Page:

Please insert -- and -- after the ";" in the description of Fig. 5.

Please cancel the description of Fig. 7.

Please cancel the description of Fig. 8.

Please cancel the description of Fig. 9.

Signed and Sealed this

Twenty-second Day of November, 1994

Attest:

BRUCE LEHMAN
